TUMBLING BARREL

Leo R. Davidson, Sturgis, Mich., assignor to The Sturgis Products Co., Sturgis, Mich., a corporation of Michigan

Application March 6, 1944, Serial No. 525,194

16 Claims. (CL 51—164)

This invention relates to improvements in Tumbling barrels.

The main objects of this invention are:

First, to provide an improved tumbling barrel which is well adapted for the practice of wet finishing methods in that it is fluid-tight and at the same time is comparatively simple and economical in structure.

Second, to provide a tumbling barrel whereby the worn out wood lining can be removed and replaced without expending labor for removing the cylinder from the machine and the heads from the cylinder.

Third, to provide a tumbling barrel having permanently associated metal ends instead of removable ends, bulkheads, and wall panels which can be readily lined without knocking down the machine.

Fourth, to provide a tumbling barrel in which the lining is mainly made up of strips or bars of wood positioned so as to effectively withstand the wear.

Fifth, to provide a lined tumbling barrel in which the liner elements are supported without the necessity for bolting to the walls of the barrel.

Objects relating to details and economies of the invention will appear from the description to follow. The invention is defined in the claims.

A preferred embodiment of the invention is illustrated in the accompanying drawing, in which:

Fig. 1 is a perspective view of a tumbling barrel with one of the removable wall panels removed, the other being in position.

Fig. 2 is a transverse sectional view on line 2—2 of Fig. 1.

Fig. 3 is a fragmentary view in partially longitudinal section on line 3—3 of Fig. 4 showing details of the liners and the relation thereof to the wall.

Fig. 4 is an enlarged fragmentary view illustrating the supporting abutting relation of the liner units to each other.

Fig. 5 is a perspective view of one of the door liner frames for one of the doors.

Fig. 6 is a perspective view of one of the assembled wall panel liner units.

Fig. 7 is an enlarged fragmentary view mainly in longitudinal section on line 7—7 of Fig. 1 showing details of the bulkhead, its liners and its relation to the wall panels.

Fig. 8 is an enlarged fragmentary section on line 8—8 of Fig. 1 showing further structural details.

Fig. 9 is a fragmentary perspective view of one of the doors.

The embodiment of my invention illustrated comprises metal polygonal end members 1 provided with journals 2. The supporting frame and bearings for these journals are not illustrated. The structure illustrated is an octagonal structure and structures having an even number of sides have certain advantages which will appear as the description proceeds.

10 The polygonal sheet metal wall member 3 is welded to the end members. This wall member comprises angularly disposed panels, there being one less panel than there are sides to the barrel. 15 The structure illustrated is a two-compartment structure and is provided with an intermediate partition or bulkhead 4 to which the side panels are welded, the bulkhead constituting a supporting and reinforcing means for the 20 wall panels, permitting the use of lighter gauge stock than would be required in tumbling barrels of the same length having only one compartment.

As stated, the wall member has one less panel than there are sides to the barrel and I provide 25 a complementary wall panel comprising a frame 5 welded to the adjacent edge of the terminal panels 6 of the wall member 3 and to the end members and bulkhead. It will be noted that this frame is of such proportions as to constitute 30 laterally projecting flanges on the panel 6 and on the end members. In the structure illustrated the frame has two openings 7.

The panel plates 8 are detachably secured to the frame by means of screws 9. The wall panel 35 10 opposite the panel constituted by the wall panel plates is provided with door openings 11, the detachable doors being shown at 12, door clamping means 13 being detachably secured by means of bolts 14.

40 The end walls and bulkhead are provided with liners 15, these liners being arranged against the sides of the end panels and bulkhead and preferably being made up of sections as indicated in Fig. 2.

45 The side walls are provided with lateral units 16 preferably made up of a series of bars 17 arranged in side by side relation and retained in assembled relation by dowels 18. These panel liners have mitered edges 19 adapted to abut 50 when they are in assembled position.

The panel having the door opening therein is provided with frame-like liner members 20 surrounding the door opening and the doors are provided with liners 21 fitting into these frame-like liner members. These frame-like liner

members constitute abutments for the adjacent panel liners 16, see Fig. 2.

The removable wall panel plates 8 are provided with liner panels 22 corresponding to the liner panels 16, these being in mitered engagement with adjacent panels and in effect constituting a key-stone element securing them all in position. The liner panels may be temporarily supported in place as, for example, by means of a prop until the assembly is complete.

The opening 7 in the frame 5 is of such dimensions as to permit the introduction of the liner units 16 in assembled relation. When introduced, the strips or bars 17 forming the liner units are spaced apart or there is sufficient slack in the assembly on the dowels so that when they become expanded or swollen they form a relatively tight continuous surface.

By thus forming these liner panels the grain of the wood is presented so that it is subject to the least amount of abrasive wear—that is, the tumbled material moves across the same in the direction of the grain and is much less likely to tear the grain and wear down the liner than it would where the movement of the material is crosswise of the grain. The doors counterbalance the frame and the panel plates.

My improved tumbling barrel can be made of relatively light stock and at the same time is strong and rigid and very durable. The body of the barrel may be formed complete and the liners readily introduced which is of substantial manufacturing advantage and also a very great advantage to the user because it makes it possible for him to re-line the barrel as the liners may become worn.

I have illustrated and described my invention in a very practical embodiment thereof. I have not attempted to illustrate or describe various modifications and adaptations which I contemplate as it is believed that this disclosure will enable those skilled in the art to embody or adapt my invention as may be desired.

Having thus described my invention, what I claim as new and desire to secure by Letters Patent is:

1. In a tumbling barrel, the combination of polygonal metal end members provided with journals, a polygonal sheet metal side wall member comprising angularly disposed panels welded to said end members, said wall member having one less panel than there are sides to the barrel, a polygonal metal bulkhead intermediate said end members and welded to said wall panels and constituting a supporting and reinforcing means therefor, a complemental wall panel comprising a frame welded to the adjacent edges of the terminal panels of said wall member and to the end members and bulkhead, wall panel plates detachably secured to said frame, the side wall panel opposite said removable wall panels having door openings therein, liners disposed against the sides of the end members and bulkhead, the width of said openings in said frame being substantially the width of a panel and the length being substantially the distance between the bulkhead and end liners, said wall panel having the door openings therein having frame-like liner members surrounding the door openings and constituting liner abutments, wall panel liner units having mitered meeting edges and comprising a plurality of bar-like pieces disposed transversely of the panels and retained in assembled side by side relation by dowels extending therethrough whereby they may be introduced into the barrel comp-

ment through said openings in said frame as assembled units and positioned in relation to their respective panels with the mitered meeting edges thereof in coacting abutting supporting relation, the panel liners adjacent said liners surrounding said door openings being in mitered abutting engagement therewith,

5 2. In a tumbling barrel, the combination of polygonal metal end members provided with journals, a polygonal sheet metal side wall member comprising angularly disposed panels welded to said end members, said wall member having one less panel than there are sides to the barrel, a polygonal metal bulkhead intermediate said end members and welded to said wall panels and constituting a supporting and reinforcing means therefor, a complemental wall panel comprising a frame welded to the adjacent edges of the terminal panels of said wall member and to the end members and bulkhead, wall panel plates detachably secured to said frame, liners disposed against the sides of the end members and bulkhead, the width of said openings in said frame being substantially the width of a panel and the length being substantially the width of a panel and the length being substantially the distance between the bulkhead and end liners, and wall panel liner units having mitered meeting edges and comprising a plurality of bar-like pieces disposed transversely of the panels and retained in assembled side by side relation by dowels extending therethrough whereby they may be introduced into the barrel compartment through said openings in said frame as assembled units and positioned in relation to their respective panels with the mitered meeting edges thereof in coacting abutting supporting relation, said removable wall panels being also provided with similar liner panels in mitered supporting relation to adjacent liner panels.

3. In a tumbling barrel, the combination of polygonal metal end members provided with journals, a polygonal sheet metal side wall member comprising angularly disposed panels welded to said end members, said wall member having one less panel than there are sides to the barrel, a polygonal metal bulkhead intermediate said end members and welded to said wall panels and constituting a supporting and reinforcing means therefor, a complemental wall panel comprising a frame welded to the adjacent edges of the terminal panels of said wall member and to the end members and bulkhead, wall panel plates detachably secured to said frame, the side wall panel opposite said removable wall panels having door openings therein, liners disposed against the sides of the end members and bulkhead, said wall panel having the door openings therein having frame-like liner members surrounding the door openings and constituting liner abutments, wall panel liner units having mitered meeting edges adapted to be introduced into the barrel compartment through said openings in said frame and positioned in relation to their respective panels with the mitered meeting edges thereof in coacting abutting supporting relation, the panel liners adjacent said liners surrounding said door openings being in mitered abutting engagement therewith,

said removable wall panels being also provided with liner panels in mitered supporting relation to adjacent liner panels, and doors for said door openings, said doors being also provided with liners, said doors and their attaching means comprising counterbalancing means for said frame and removable wall panels.

4. In a tumbling barrel, the combination of polygonal metal end members provided with journals, a polygonal sheet metal side wall member comprising angularly disposed panels welded to said end members, said wall member having one less panel than there are sides to the barrel, a polygonal metal bulkhead intermediaite said end members and welded to said wall panels and constituting a supporting and reinforcing means therefor, a complemental wall panel comprising a frame welded to the adjacent edges of the terminal panels of said wall member and to the end members and bulkhead, wall panel plates detachably secured to said frame, liners disposed against the sides of the end members and bulkhead, and wall panel liner units having mitered meeting edges adapted to be introduced into the barrel compartment through said openings in said frame and positioned in relation to their respective panels with the mitered meeting edges thereof in coacting abutting supporting relation, said removable wall panels being also provided with liner panels in mitered supporting relation to adjacent liner panels.

5. In a tumbling barrel, the combination of polygonal metal compartment end members, a polygonal sheet metal side wall member comprising angularly disposed panels welded to said end members, said wall member having one less panel than there are sides to the barrel, a complemental wall panel comprising a frame welded to the adjacent edges of the terminal panels of said wall member and to said end members, wall panel plates detachably secured to said frame, the side wall panel opposite said removable wall panels having a door opening therein, liners disposed against the sides of said end members, the width of said openings in said frame being substantially the width of a panel and the length being substantially the distance between the end liners, said wall panel having the door opening therein having a liner member constituting a liner abutment, wall panel liner units having mitered meeting edges and comprising a plurality of bar-like pieces disposed transversely of the panels and retained in assembled side by side relation by dowels extending therethrough whereby they may be introduced into the barrel compartment through said openings in said frame as assembled units and positioned in relation to their respective panels with the mitered meeting edges thereof in coacting abutting supporting relation, the panel liner adjacent said liner surrounding said door opening being in mitered abutting engagement therewith, said removable wall panels being also provided with a similar liner panel in mitered supporting relation to adjacent liner panels, and a door for said door opening, said door being also provided with a liner, said door and its attaching means comprising counterbalancing means for said frame and removable wall panel.

6. In a tumbling barrel, the combination of polygonal metal compartment end members, a polygonal sheet metal side wall member comprising angularly disposed panels welded to said end members, said wall member having one less panel than there are sides to the barrel, a complemental wall panel comprising a frame welded to the ad-

jacent edges of the terminal panels of said wall member and to said end members, wall panel plates detachably secured to said frame, liners disposed against the sides of said end members, and wall panel liner units having mitered meeting edges and comprising a plurality of bar-like pieces disposed transversely of the panels and retained in assembled side by side relation by dowels extending therethrough whereby they may be introduced into the barrel compartment through said opening in said frame as an assembled unit and positioned in relation to their respective panels with the mitered meeting edges thereof in coacting abutting supporting relation, said removable wall panels being also provided with a similar liner panel in mitered supporting relation to adjacent liner panels.

7. In a tumbling barrel, the combination of polygonal metal compartment end members, a polygonal sheet metal side wall member comprising angularly disposed panels welded to said end members, said wall member having one less panel than there are sides to the barrel, a complemental wall panel comprising a frame welded to the adjacent edges of the terminal panels of said wall member and to said end members, wall panel plates detachably secured to said frame, the side wall panel, opposite said removable wall panels having a door opening therein, liners disposed against the sides of said end members, the width of said opening in said frame being substantially the width of a panel and the length being substantially the distance between the end liners, said wall panel having the door opening therein having a liner member constituting a liner abutment, wall panel liner units having mitered meeting edges adapted to be introduced into the barrel compartment through said opening in said frame as an assembled unit and positioned in relation to their respective panels with the mitered meeting edges thereof in coacting abutting supporting relation, the panel liner adjacent said liner surrounding said door opening being in mitered abutting engagement therewith, said removable wall panels being also provided with a liner panel in mitered supporting relation to adjacent liner panels, and a door for said door opening, said door being also provided with a liner, said door and its attaching means comprising counterbalancing means for said frame and removable wall panel.

8. In a tumbling barrel, the combination of polygonal metal compartment end members, a polygonal sheet metal side wall member comprising angularly disposed panels welded to said end members, said wall member having one less panel than there are sides to the barrel, a complemental wall panel comprising a frame welded to the adjacent edges of the terminal panels of said wall member and to said end members, wall panel plates detachably secured to said frame, liners disposed against the sides of said end members, and wall panel liner units having mitered meeting edges adapted to be introduced into the barrel compartment through said opening in said frame and positioned in relation to their respective panels with the mitered meeting edges thereof in coacting abutting supporting relation, said removable wall panels being also provided with a liner panel in mitered supporting relation to adjacent liner panels.

9. In a tumbling barrel, the combination of polygonal metal compartment end members, polygonal sheet metal side panels welded to said end members, there being one less side panel

than there are sides to the barrel, and a complemental wall panel comprising a frame disposed with its inner longitudinal edges substantially flush with the adjacent edges of the adjacent side wall panels to project outwardly from such edges and welded thereto and to said compartment end members, and a wall panel plate detachably secured to said frame, the width of the opening of said frame being substantially the width of a panel and the length being such as to permit the introduction and removal of wall panel liner units and the positioning thereof in relation to their respective panels.

10. In a tumbling barrel, the combination of polygonal metal compartment end members, polygonal sheet metal side panels welded to said end members, there being one less panel than there are sides to the barrel, and a complemental wall panel comprising a frame disposed with its inner longitudinal edges substantially flush with the adjacent edges of the adjacent wall panels to project outwardly from such edges and welded thereto and to said end members, the width of the opening of said frame being substantially the width of a panel and the length being such as to permit the introduction and removal of wall panel liner units and the positioning thereof in relation to their respective panels, and a closure for said opening detachably secured to said frame.

11. In a tumbling barrel, the combination of polygonal compartment end members, sheet metal side wall panels fixedly secured to said compartment end members, there being at least one less of said side wall panels than there are sides to the barrel, and a complemental wall panel comprising a frame disposed with its inner longitudinal edges substantially flush with the adjacent edges of adjacent side wall panels to project outwardly from such edges and fixedly secured thereto and to said compartment end members, the width and length of the opening of said frame being such as to permit the introduction and removal of panel liner units through the opening, and a closure for said opening provided with a liner.

12. In a tumbling barrel, the combination of polygonal metal compartment end members, polygonal sheet metal side panels welded to said end members, there being one less side panel than there are sides to the barrel, and a complemental wall panel comprising a frame disposed with its inner longitudinal edges substantially flush with the adjacent edges of the adjacent side wall panels to project outwardly from such edges and welded thereto, and a wall panel plate detachably secured to said frame, the width of the opening of said frame being substantially the width of a panel and the length being such as to permit the introduction and removal of wall panel liner units and the positioning thereof in relation to their respective panels.

13. In a tumbling barrel, the combination of polygonal metal compartment end members, and polygonal sheet metal side panels welded to said end members, one of said side panels comprising a frame disposed with its inner longitudinal edges substantially flush with the adjacent edges of

5 the adjacent side panels to project outwardly from such edges and welded thereto, and a side panel plate detachably secured to said frame, the width of the opening of said frame being the width substantially of one of said side panels and the length being such as to permit the introduction and removal of side panel liner units and the positioning thereof in relation to their respective panels.

14. In a tumbling barrel, a polygonal metal compartment comprising polygonal end members, polygonal sheet metal side panels permanently joined to said end members, one of said side panels comprising a frame disposed with its inner longitudinal edges substantially flush with the adjacent edges of the adjacent side wall panels to project outwardly from said edges, the frame and said edges being permanently secured together, and a removable panel plate detachably secured to said frame, the width of the opening of said frame being at least equal to the width of a panel and the length being such as to permit the introduction of wall panel liner units and the positioning thereof in relation to their respective panels.

15. In a tumbling barrel, a polygonal metal compartment comprising polygonal end members, polygonal sheet metal side panels permanently joined to said end members, one of said side panels comprising a frame disposed with its inner longitudinal edges substantially flush with the adjacent edges of the adjacent side wall panels to project outwardly from said edges, the frame and said edges being permanently secured together, and a removable panel plate detachably secured to said frame, the width of the opening of said frame being at least equal to the width of a panel and the length being such as to permit the introduction of wall panel liner units and the positioning thereof in relation to their respective panels, and another of said side panels directly opposite the first named panel comprising a door supporting panel having a door opening therein whereby liner units can be pushed out through the opening of said frame by a tool inserted in the door opening.

16. In a tumbling barrel, a polygonal metal compartment comprising polygonal end members, polygonal sheet metal side panels permanently joined to said end members, one of said side panels comprising a frame disposed with its inner longitudinal edges substantially flush with the adjacent edges of the adjacent side wall panels to project outwardly from said edges, the frame and side edges being permanently secured together, and a removable panel plate detachably secured to said frame, the width of the opening of said frame being at least equal to the width of a panel and the length being such as to permit the introduction of wall panel liner units and the positioning thereof in relation to their respective panels, and another of said side panels directly opposite the first named panel comprising a door supporting panel having a door opening therein, the adjacent panels to said door panel having door mounting brackets thereon.

LEO R. DAVIDSON.
